PUNCHING DIE

John F. Kopeczynski, Buffalo, N. Y.

Application May 31, 1946, Serial No. 673,713

1 Claim. (Cl. 164—124)

1

This invention relates to tools and particularly to punches for punching holes or apertures in sheets.

In punching apparatus the punch element has a reduced end portion or stem which does the punching, and an intermediate or junction part connecting the main body portion with the reduced end portion or punching end. This intermediate part increases progressively in cross sectional area through a plurality of stages from the reduced end to the body portion. Considerable difficulty has been experienced with punch elements of this type, owing to the fact that the reduced end portion frequently breaks off at approximately its junction with the intermediate part. The cause of such breakage is due to a whipping of the reduced end of the punch element, caused by the stresses created in the actual punching operation. When such a breakage occurs, the punch must be replaced by a new punch which in itself is a substantial expense, and also causes delay while the punch element is being replaced and aligned.

An object of this invention is to provide an improved punch device or tool; with which punching operations may be performed in the usual manner; with which breakage and wear of the punch element are substantially reduced or eliminated; which will not interfere with the usual operations of the tool; with which the initial cost of the tool will be relatively small; and which will be practical and relatively simple.

Another object of the invention is to provide an improved punch element with a ground surface on the punching end, in which the ground grain runs parallel to the longitudinal axis of the end; with which the picking up of small particles of stock by the reduced punch end will be reduced to a minimum; with which the tendency of the punch element to crack and break will be reduced; with which a more perfect blending between the reduced end and tapered portion may be obtained; with which heating of the punch during grinding is reduced; and which will be relatively simple, practical, inexpensive, and of long life.

Another object is to provide an improved and simple punch assembly in which the punch element will be guided in the stripper at a position remote from its advance, punching end; with which wear in the guide will be reduced to a minimum; and with which guides for the punch element may be interchangeably mounted in the stripper for use in guiding different sizes of punch elements.

2

Another object is to provide improved and simple means for securing a guide sleeve on a punch element, with which the sleeve will be securely anchored to said element against forces created during punching operations and tending to displace said sleeve along the punch element.

Another object is to provide an improved and simple method of grinding the sides of a punch element to reduce it accurately to the desired size, and to form thereon a ground grain running parallel to the longitudinal axis of the punching end of the punch element; and with which one may obtain a more perfect blending or merging of the punching end into the tapered section connecting the punching end to the body of the punch element.

Other objects and advantages will be apparent from the following description of one embodiment of the invention, and the novel features will be particularly pointed out hereinafter in connection with the appended claim.

In the accompanying drawing:

Fig. 1 is a sectional elevation of a punch assembly constructed in accordance with this invention;

Fig. 2 is a sectional plan of a part of the same, the section being taken approximately along the line 2—2 of Fig. 1;

Fig. 3 is an elevation of the lower part of the punch element, with a diagram illustrating the improved method of grinding the punching stem and adjoining tapered section of the punch element; and

Fig. 4 is a sectional elevation of the sleeve or collar to be mounted on the punching element.

In the illustrated embodiment of the invention, a punch element 1 is suitably but detachably mounted in a die head 2 which moves towards and from a die base 3 having a female die opening 4 along its upper surface, with a downwardly enlarging passage 5 connected to the opening 4 for the discharge of slugs. The punch element 1 has its base or body part mounted in the head 2 in any suitable manner, such, for example, as disclosed in my Patent No. 2,329,061 and in my copending application for patent, Ser. No. 595,318 filed May 23, 1945.

The punch element 1 carries a punching end or stem 6 which has a size and shape to pass through the opening 4, with a proper clearance, for piercing a blank or stock 7 of metal or any other suitable sheet material. This punch end 6 is joined to the body part of the punch element by a tapered transition part 8 (see Fig. 3) which has its smaller end merging into its piercing end

6. A sleeve or collar on the punch element 9 is provided with a tapered, interior passage 10 merging at one end into a straight passage section 11 having the shape of the punching end 6 and a size to have a press fit therewith. The tapered part 10 of the passage fits the tapered part 8 of the punch element rather snugly. A pin 12 extends transversely through the sleeve 9 and the tapered transition part 8 of the punch element while the sleeve is snugly fitted on the punch element against tapered part 8. This pin 12, supplementing the press fit, positively locks the sleeve on the punch element and resists endwise pulls on the sleeve tending to dislodge it from its fitting engagement against the tapered surface of the part 8 of the punch element.

A stripper member 13 disposed above the blank 7, is either directly carried by the base 3 or preferably, as shown, is carried by rods 14 and springs 15 on the die head 2 and forms what is known as a pressure stripper. This invention is not concerned with whether the stripper member 13 is carried by the die head 2 as a pressure stripper, or rigidly on the base, both being well known types of mounting for the stripper member. The stripper member 13 is, however, provided with a passage 14 which snugly fits the punching end 6 of the punch element, and through which this punching end 6 is adapted to move during a punching operation. This snug, sliding fit between the punching end 6 of the punch element and the passage 14 is preferably along the lower edge of the stripper member, so as to give support to the punch end of the punch element as closely as possible to the blank 7 being perforated. The stripper member 13 also has a larger passage 15 above passage 14 in which the sleeve 9 snugly and slidingly fits during the punching operation, so as to guide and support the punch element at the junction of the punching end with the tapered part 8 of the punch element.

Any whipping of the punching end 6 of the punch element is avoided by the engagement of the collar or sleeve 9 with the side wall of the passage 15, and the passage 15 is deep enough to enable the punch to make its full stroke before the sleeve 9 reaches the bottom of the passage 15. This guiding support for the punch effectively reduces or largely eliminates the breakage of the punch heretofore experienced, and for the first time makes it possible to pierce blanks of greater thickness than the diameter of the piercing tool. The periphery of the sleeve or collar 9 is machined to its proper size, preferably the same diameter as that of the main body of the punch element.

While the punch element in the drawing is illustrated as formed to pierce round apertures in the blank or work sheet, and the collar or sleeve 9 has a circular periphery, it will be understood that either or both of the punching end of the punch and the sleeve 9 may have non-circular peripheries of any particular design, depending upon the character of the aperture to be punched in the blank or work. The passages in the stripper in which the punching end of the punch element and the sleeve 9 reciprocate, will always, of course, conform in character or shape to the character or shape of the surface of the punching end and sleeve. With the punch element re-enforced by the sleeve 9 slidingly guided in this manner, it has been possible to successfully punch apertures in blanks having a thickness more than twice

the diameter of the punch or aperture, and do so in production for long periods of time without requiring re-grinding the punch element.

Inasmuch as the punch element is usually hardened before the sleeve 9 is applied thereto, it is preferable to form a transverse passage 17 in the tapered part 8 of the punch element, before the punch element is hardened. When the sleeve or collar 9 is to be applied, the hardened punch element is mounted in a drill press, but not rotating, with the drill in the passage 17, and then while the punch element remains anchored in that position and not rotating, the drill is withdrawn from the passage 17, the collar or sleeve 9 applied over the punch element with a press fit, and then the drill brought down while rotating to drill a hole in the sleeve 9 which will be in perfect alignment with the passage 17. The drill is then withdrawn and the dowel or coupling pin 12 passed through the aligned passages in the sleeve 9 and tapered part 8 of the punch element. In this way it is practical to harden or temper the punch element after the passage 17 is formed and before the sleeve 9 is applied.

The sleeve 9 is preferably made of bearing metal, such as bearing bronze, and it has been found that in such cases wear is reduced between the sleeve and the passage 15 in the stripper 13. Bearing metals such as bearing bronze are considerably softer than the tool steel of which the punches are made and the tool steel is tempered to harden it. The relatively soft metal on the surface layer of the sleeve or the entire sleeve when made of soft metal acts as a damper to damp vibrations of the punch. When a punch engages a sheet metal blank at the instant the piercing of the blank starts, the impact is rather heavy, and this sets up a lateral vibration on the punch which tends to snap the punch and cause molecular fatigue of the punch at the junction of the tapered part of the punch and the punching end. The softer metal absorbs and damps these vibrations so as to greatly reduce the breakage of the punches. The thicker the metal of the blank, the greater the impact and, consequently, the greater the vibration tendency of the punch. A piece of rubber or soft material on a prong of a tuning fork will absorb the vibrations or damp them, and this soft metal appears to damp or absorb the vibrations of the punch, and therefore, it is possible to increase the thickness of the sheet metal which can be successfully pierced by a punch. Preferably the guide passages in the stripper 13 for the punch element are provided in a separate sleeve or member 19 which is removably secured in an aperture in the stripper 13, so that when different size punches are interchangeably placed in the die head 2, a suitably formed liner 19 having passages 14 and 15 fitting those of the punching end 6 of the punch element and the periphery of the sleeve 9 may be inserted in the stripper 13. If desired, the liner 19 may be made of bearing metal, in which event the sleeve 9 may also be made either of bearing metal or hardened steel or other material.

It is also desirable in punches which have a ground punching end, to have the ground grain on the periphery of the punching end of the punch element run lengthwise of the punch element. Heretofore the ground grain, that is, the grain surface produced by grinding, extended peripherally around the punch element because

the grinding usually occurred by rotating the punch element. In such cases, the cross ground grain tended to pick up small pieces of stock and bind in the blank and female die. In Fig. 3 is illustrated diagrammatically an improved method of grinding the punching end 6 of a punch element in a manner to have the ground grain run lengthwise of the punch element, to avoid having the punch element pick up pieces of stock, and to have the punching end blend easily into the tapered part 8.

Referring now to Fig. 3 in which the grinding action is shown diagrammatically, it will be understood that the punch element 1 is mounted in the usual lathe chuck for rotation about its axis, as usual in grinding such punches heretofore, and on the tool stock (not shown) of the lathe carriage, is mounted a grinding wheel 20, the spindle 21 of which is vertical, that is, with its axis in a plane which is parallel to the axis of rotation of the punch element but offset therefrom. This spindle 21 being mounted on the tool stock is first shifted by movement of the tool stock until the grinding wheel 20 engages the periphery of the punching stem of the punch element. While the punch element 6 is rotating very slowly with the chuck of the lathe, the grinding wheel 20 is independently rotated at high speed with the spindle 21 and slowly shifted, by travel of the lathe carriage along line A—A, parallel to the axis of the punch element, to grind the punch end to the desired size. After the tool stock has been moved with the carriage along the lathe bed until the grinding wheel 20 reaches the desired junction between the punching stem and the tapered part 8, the travel of the carriage is ended.

While the carriage of the lathe mounting the tool stock remains in this position, the top part of the tool stock which mounts the grinding wheel spindle 21 is on the carriage at an angle to the axis of the punch in the direction of the line B—B, which is parallel to the tapered edge 8 of the punch element. During this movement both the grinding wheel 20 and the punch element are rotating at the same time, which grinds the desired taper 8 on the punch element with a very careful and accurate blending between the straight section of the punching end and the tapered part of the punch element. The small surface of contact between the grinding wheel and

the punch element reduces heating of the punch element to a minimum. Because of the high speed of the grinding wheel in relation to the slow rotation of the punch element 1, the ground grain runs substantially lengthwise of the element 1.

It will be understood that various changes in the details, materials and arrangements of parts, which have been herein described and illustrated in order to explain the nature of the invention, may be made by those skilled in the art within the principle and scope of the invention, as expressed in the appended claim.

I claim:

A tool comprising a body portion, a convergingly tapered portion on one end of the body portion, and a cylindrical punching end portion, of uniform cross sectional area along its length, forming an extension of the smaller end of said tapered portion and merging into said tapered portion in a concave curve, said punching end portion having a ground peripheral surface continuous throughout said end portion and up the smaller end of the tapered portion, with the ground grain of that surface running in a direction lengthwise of said punching end and tapered portions, a sleeve having a passage fitting and telescoping snugly with the full length of said tapered portion and with a substantial and adjacent part of said punching end portion, and a mechanical interlock between said sleeve and punch to secure said sleeve against endwise movement on the tapered portion.
